Inventor:

UNITED STATES PATENT OFFICE.

BERNARD REICHENBACH, OF NEW YORK, N. Y.

DESIGN FOR A BOX FOR A SET OF BUILDING-BLOCKS OR SIMILAR ARTICLE.

58,940.

Specification for Design.

Patented Sept. 6, 1921.

Application filed December 8, 1920. Serial No. 429,286. Term of patent 7 years.

To all whom it may concern:

Be it known that I, BERNARD REICHENBACH, a citizen of the United States, residing at New York city, in the county and State of New York, have invented a new, original, and ornamental Design for a Box for a Set of Building-Blocks or Similar Article, of which the following is a specification, reference being had to the accompanying drawing, forming a part thereof.

The drawing is a view of the box for a set of building blocks showing my new design.

I claim—

The ornamental design for a box for a set of building blocks or similar article, as shown.

In testimony whereof I affix my signature.

BERNARD REICHENBACH.
